(57) **CLAIM**

The ornamental design for a surface mount for a mobile device, as shown and described.

DESCRIPTION

FIG. 1 is a perspective front view of a surface mount for a mobile device showing our new design.

FIG. 2 is an elevational front view of the surface mount for a mobile device.

FIG. 3 is an elevational back view of the surface mount for a mobile device.

FIG. 4 is a top plan view of the surface mount for a mobile device.

FIG. 5 is a bottom plan view of the surface mount for a mobile device.

FIG. 6 is a left side elevational view of the surface mount for a mobile device.

FIG. 7 is a right side elevational view of the surface mount for a mobile device; and,

FIG. 8 is a right side elevational front view of the surface mount for a mobile device engaged with a mobile device case.

The broken lines illustrate portions of the surface mount for a mobile device that form no part of the claimed design. Additional broken lines showing a mobile device in FIG. 8 illustrate environment and form no part of the claimed design.

1 Claim, 6 Drawing Sheets
